US00D617798S

(12) United States Design Patent
Liu

(10) Patent No.: US D617,798 S
(45) Date of Patent: * Jun. 15, 2010

(54) STYLUS

(75) Inventor: Hang Liu, Beijing (CN)

(73) Assignee: Nokia Corporation, Espoo (FI)

() Term: 14 Years

(21) Appl. No.: 29/329,993

(22) Filed: Dec. 24, 2008

(51) LOC (9) Cl. 14-02

(52) U.S. Cl. D14/411

(58) Field of Classification Search D8/61; D14/411; D19/35, 36, 41-51, 54-58; 401/55, 401/99, 100, 104-107, 196, 197, 202, 208, 401/209, 213, 192, 195, 243; 708/107; 345/179, 345/173; 178/19.01; 700/94

See application file for complete search history.
